ERNEST R. BURNS, OF SEATTLE, WASHINGTON.

SEAL-HASP.

1,078,534.

Specification of Letters Patent. Patented Nov. 11, 1913.

Application filed February 10, 1913. Serial No. 747,451.

To all whom it may concern:

Be it known that I, ERNEST R. BURNS, citizen of the United States, residing at Seattle, in the county of King and State of Washington, have invented a certain new and useful Improvement in Seal-Hasps, of which the following is a specification.

My invention relates to improvements in seal-hasps and more particularly it relates to seal-hasps that are adapted to be used on railroad freight cars to fasten and seal their doors.

The object of my improvement is to provide a seal-hasp which shall be strong, durable, simple in construction and reliable in its operation and which is adapted to be sealed with a seal that may cost but little to make, such seal being readily accessible for quick inspection; and a further object of my improvement is to provide seal-hasps one of which cannot possibly be unhasped without breaking some part of it or making it clearly observable that its seal has been mutilated. I attain these objects by devices illustrated in the accompanying drawings, wherein—

Figure 1 is a view in side elevation of a seal-hasp containing my invention as applied to a fragment of a door frame of a car, Fig. 2 is a view in front elevation of the same in which some parts are shown in vertical-section on broken line x, x of Fig. 1, Fig. 3 is a view in vertical-section of the same (on broken line y, y of Fig. 2) except that two movable parts are shown in side elevation, Fig. 4 is a fragmentary view of the same in front elevation (with some parts shown in vertical-section on broken line x, x of Fig. 1) but wherein its bolt-shaft is turned to a position that is 90 degrees distant from the position of the same bolt-shaft as shown in Fig. 1, Fig. 5 is a view in horizontal cross-section of the same on broken line z, z of Fig. 4, and Fig. 6 is a view in horizontal cross-section of a bolt-shaft on broken line w, w of Fig. 4.

Like reference numerals indicate like parts throughout the drawings.

Referring to the drawings, 7 represents a door-post of a railway freight car upon which is fastened the base 8 of a seal-hasp by bolts 9, 9. Extending outwardly from said base 8 and integral therewith is the bolt-shaft barrel 10 and a bolt-socket 11, said bolt-socket 11 is projecting through the oblong hole 12 of a hasp strap 13 a fragment

of which is shown in Fig. 2 and which may be supposed to be fastened upon a freight car door not shown. A bolt-shaft 14, as shown in Fig. 1, is disposed within the bolt-shaft barrel 10 to extend downwardly to project into the bolt-socket 11 to secure the hasp-strap 13 in its position on the bolt-socket 11.

Figs. 1, 2 and 3 illustrate the position of the shaft-bolt 14 when a car door to which the device is applied is locked and sealed, the sealing being effected by a seal made of thin sheet metal, preferably of thin tin plate, in the form of a narrow strip which is provided in its central portion with an elongated hole 16, said seal being disposed in a rectangular shaped hole 17 that extends diametrically through the said bolt-shaft 14 so that each of its end portions projects from its side of the bolt-shaft 14 for a suitable distance to afford surface upon which may be stamped or inscribed distinctive numbers or characters. The bolt-shaft 14 is provided with a longitudinal slotted hole 18 that extends through it from side to side in a place at right angles with the hole 17 and in a position to intersect said hole 17 and within such slotted hole 18 is disposed a pawl 19 which is pivoted by a pin 20 to swing freely within said slotted hole 18, said pawl 19 being provided with a projecting tongue 21 that is adapted by its position with relation to the hole 17 to project through the oblong hole 16 of a seal 15 when such seal 15 is inserted in the hole 17 to assume its position therein as shown in Fig. 2, whereby said seal 15 may be securely locked within the hole 17 by said tongue 21, as more clearly indicated in Fig. 3. To insert the seal 15 into and through the hole 17 the bolt-shaft 14 (when in the circumferential position shown in Fig. 4) is moved to its farthest downward extent to extend its end through the bolt-socket 11 which will bring the pawl 19 low enough to permit its wider end to be projected out of its slotted hole 18 far enough to remove its tongue 21 from a position to obstruct the insertion of the seal 15, (but such position is not illustrated in the drawings) and after a seal 15 is inserted the bolt-shaft 14 is turned circumferentially for a distance of 90 degrees and then drawn upwardly until it assumes the position shown in Fig. 3, whereupon another pawl 22, which is pivotally disposed within another slotted hole 23, is caused by

a spiral compression spring 24, to project an angular corner into a recess 25 in the frame of the bolt-shaft barrel 10, as shown in Fig. 3, whereby the bolt-shaft 14 may not be moved downwardly again until the seal 15 is broken or cut to remove it from the hole 17, and said bolt-shaft 14 cannot be raised from its position, as shown in Fig. 3, without mutilating the seal 15 since the pawl 19 projects outwardly from the slotted hole 18 and held there by the seal 15 so that the wider end of said pawl 19 cannot be raised into the bolt-shaft barrel 10 without cutting or mutilating the seal 15 and furthermore, the bolt-shaft 14 cannot be turned circumferentially from its position as shown in Fig. 3, since the end of a screw 26 is disposed to project within the slotted hole 18 at all times except when the bolt-shaft 14 is in its lowest position at which time the end of said screw 26 will register with a circumferential slot 27 which extends for a distance of 90 degrees, or more, from the slotted hole 18, and except when the bolt-shaft 14 is raised to its highest position when the end of the screw 26 will register with another longitudinal slot 28 disposed at a point near the lower end of the bolt-shaft 14 to extend circumferentially for a distance of more than 90 degrees from the slotted hole 18. Thus with the bolt-shaft 14 disposed in the position, as shown in Fig. 3, to secure the hasp-strap 13 in its position on the bolt-socket 11 such bolt-shaft 14 cannot be moved in any direction without cutting or mutilating the seal 15 to an extent that would be readily observable.

When the bolt-shaft 14 is not sealed by a seal 15 and it is desired to retain it in its uppermost position as shown in Fig. 4, it is only necessary to turn it 90 degrees from the position from which it is shown in said Fig. 4 whereupon the angular corner of the pawl 22 in response to the action of the spring 24 will project more and more outwardly from its slotted hole 23 as it follows the cam-like surface 29 of the upper end of the barrel 10 as illustrated in Fig. 5, until the pawl 22 reaches the position indicated by the dotted lines in said Fig. 5, in which position the said angular corner of the pawl 22 will engage with the flat surface 30 on the end of the barrel 10, thus to retain the bolt-shaft 14 in its highest position whereby the hasp-strap 13 may be placed over the bolt-socket 11 and obviously to shoot the bolt downwardly into the socket 11 it is only necessary to turn the shaft-bolt 14 in a counter-clock-wise direction to the position shown in Fig. 5, whereupon the cam-like surface 29 will force the pawl 22 inwardly so that the bolt-shaft 14 may pass to its lowest point to lock the hasp-strap 13 on the bolt-socket 11 and at such lowest point the seal 15 may be inserted whereupon the bolt-shaft 14 may be

turned back 90 degrees and raised to the position shown in Fig. 3, there to be locked by the pawl 22 with respect to downward movement and by the end of the screw 26 with respect to circumferential movement and by the pawl 19 with its tongue 21 and the seal 15 with respect to its upward movement and hence said bolt-shaft 14 may not be withdrawn from the bolt-socket 11 without destroying or observably mutilating the seal 15. I have shown a turn-pin 31 secured in the upper end portion of the bolt-shaft 14 to facilitate the manipulation of said bolt-shaft 14.

In Fig. 6, I have shown by a view in cross-section on line *w*, *w* of Fig. 4, the bolt-shaft 14 and the circumferential slot 28.

Obviously many modifications of the various parts of my invention, may be made, in the form and dimensions without departing from the spirit thereof.

What I claim is:

1. In a seal-hasp of the class described, the combination with a bolt-shaft barrel which is associated with a supporting base plate, of a bolt-shaft socket, a bolt-shaft adapted to be moved in a lengthwise direction within said bolt-shaft barrel to cause it to enter and withdraw from said bolt-shaft socket said bolt-shaft being provided with a longitudinal slot, a pawl which is provided with a tongue that projects from one of its edges and which is pivotally disposed within said longitudinal slot in said bolt-shaft, a hole in said bolt-shaft disposed to extend therethrough from side to side with its axis at right angles with said longitudinal slot and to register with the path of said tongue of said pawl, and sealing means adapted to be disposed in said hole normally to maintain said pawl in a position wherein a portion of it will project outwardly from said longitudinal slot in said bolt-shaft whereby said bolt-shaft may not be withdrawn from said bolt-shaft socket without causing said pawl to mutilate said seal.

2. In a seal-hasp of the class described, the combination with a bolt-shaft provided with recesses extending longitudinally therein, of a pawl pivotally disposed within one of said recesses, retractile means associated with said pawl and said bolt-shaft and disposed to adapt it to cause said pawl normally to project for a suitable distance outwardly from said bolt-shaft, another pawl pivotally disposed within another of said recesses, and sealing means associated with said last named pawl and said bolt-shaft whereby such last named pawl may be caused normally to project outwardly from said bolt-shaft.

3. In a seal-hasp of the class described, the combination with a suitably supported bolt-shaft barrel, of a bolt-shaft socket, a hasp-strap adapted to be locked on said bolt-

shaft socket, a bolt-shaft adapted to be moved in said bolt-shaft barrel to cause it to lock and unlock said hasp-strap on said bolt-shaft socket said bolt-shaft being provided with pawls pivotally disposed in association with it so that one of said pawls may be actuated to sustain said bolt-shaft in an uppermost position where it is disengaged from said bolt-shaft socket while the other 10 of said pawls is adapted to be caused to assume a position whereby it may prevent an upward movement of said bolt-shaft in said

bolt-shaft barrel and sealing means adapted to maintain said last named pawl in such position as will prevent said upward movement of said bolt-shaft in said bolt-shaft barrel. 15

In witness whereof, I hereunto subscribe my name this first day of February A. D., 1913.

ERNEST R. BURNS.
